UNITED STATES PATENT OFFICE.

EDWARD SMULSKI, OF BROOKLINE, MASSACHUSETTS.

CONCRETE-REINFORCING MEANS.

1,245,395.

Specification of Letters Patent. Patented Nov. 6, 1917.

Application filed April 3, 1916. Serial No. 88,431.

To all whom it may concern:

Be it known that I, EDWARD SMULSKI, a citizen of the United States, and a resident of Brookline, Massachusetts, have invented an Improvement in Concrete-Reinforcing Means, of which the following description, in connection with the accompanying drawings, is a specification, like characters on the drawings representing like parts.

10 This invention relates to means for reinforcing concrete and the like, and among other objects provides a reinforcing beam for interlocking engagement with the concrete to produce effective reinforcement 15 therefor with economy of material.

The character of the invention may be best understood by reference to the following description of an embodiment illustrating the invention shown in the accompanying 20 drawings, wherein,—

Figure 1 is a plan view of a concrete slab equipped with a reinforcing beam illustrating the invention;

Fig. 2 is a vertical section taken on line 25 2—2 of Fig. 1;

Fig. 3 on an enlarged scale is a vertical section through a portion of the slab and a beam shown in Figs. 1 and 2;

Fig. 4 is a side elevation of a portion of 30 the beam;

Fig. 5 is a vertical section through the beam;

Fig. 6 is a plan view of a portion of the beam;

Fig. 7 is a view showing the bottom of 35 the tension reinforcing flange of the beam.

Referring to the drawings, 1 designates a concrete slab, the term being used in a broad or comprehensive sense, supported by 40 suitable columns 3 which may be in the form of I-beams embedded in concrete. A pair of said columns 3 may be connected by a reinforcing beam 5, and an adjacent pair of the columns may be connected by a 45 similar reinforcing beam 5. Said reinforcing beams in turn may be connected by similar reinforcing side beams 7 and a beam 9 extending across the slab centrally between said beams 7.

50 To further reinforce the slab, tension rods 10 may be provided extending across the tops of the beams and bent downward to present portions between said beams adjacent the lower surface of the slab.

55 Each of the beams 5, 7 and 9 in the present instance of the invention projects from

a point adjacent the upper surface of the slab down and is embedded in a depending rib 11 (Fig. 2) of the slab.

Referring now more particularly to Figs. 60 3 to 7 inclusive, the reinforcing beam there shown comprises a flange 13 for resisting tension stresses in the concrete, a web 15 for resisting shearing stresses therein, and a head or flange 17 for resisting compression 35 stresses therein.

The compression reinforcing flange is relatively small as compared with the tension reinforcing flange. In fact, the former may be merely slightly wider than the 70 thickness of the web of the beam. To enable this reduction in the size of the aforesaid flange, means is provided for locking or anchoring the same to the concrete typified herein as a series of elements or projections 19 extending in "hill-and-valley" 75 form along the top of the flange, and series of lateral projections 21 at the edges of the flange in staggered relation opposite grooves 23. The lateral projections thus formed do 80 not detract from the strength of the beam.

The anchoring elements preferably are distributed substantially throughout the length of the flange, and thereby provide 85 an interlocking of the flange with the concrete at points distributed substantially throughout the length of the beam adjacent the upper surface of the slab where the concrete experiences compression stresses. Thus the concrete and beam will effectively 90 resist these stresses and flexion of the beam.

The portion of the slab adjacent the lower surface thereof between columns is subjected to tension stresses. Concrete, however, is 95 weak in resisting such stresses. Similarly, the portion of the concrete beam 11 adjacent the lower surface thereof, experiences tension stresses and is weak in resisting such stresses. Therefore, to strengthen the slab and the concrete beam, or either of them, 100 against tension stresses, the flange 13 of the beam may be made large and of a width very substantially greater than the flange 17.

To interlock or anchor the flange 13 with the concrete, it may have anchoring elements 105 or projections distributed along the same. As shown herein, the flange is provided with series of edge projections 25 in staggered relation and alternating with grooves 27 without loss of material and strength. The 110 outer face of the flange may have a series of grooves or channels extending longitudi-

nally thereof forming ribs which will prevent the thin layer of concrete beneath said face from flaking or breaking therefrom in much the same manner as spaced laths will hold plaster on a ceiling.

The web of the beam may be provided with elements for interlocking or anchoring the same with the concrete, shown herein as apertures 21, projections 23 and lugs 25. The locking elements for the web have an important advantage since they combine or unite the web with the concrete, effectively prevent slip between them, and thereby materially increase the resistance of the beam to shearing stresses. Furthermore, the interlocking of the web with the concrete enables a much thinner web to be used than heretofore with substantial economy of material.

It will be understood the concrete is relied upon principally to resist compression. Therefore the compression reinforcing flange 17 might be further reduced in width, but it is desirably made substantially of the width shown in order to furnish strength to the beam during the process of construction, where it is called upon to support loads prior to the embedding of the beam in the concrete.

When a load is placed on a slab reinforced by an I-beam, the beam will tend to sag downward intermediate its ends. The lower flange of the beam will experience tension stresses, the upper flange of the beam will experience compression stresses, and the web of the beam will experience shearing stresses. The beam cannot sag or arch downward without sliding relatively to the concrete and heretofore there has been no provision for adequately preventing such sliding, but by my invention the beam and concrete are so interlocked that the compression

strength of the concrete is utilized by the beam, thereby enabling the size thereof to be materially reduced without sacrificing the strength of construction.

Upper surface portions of the slab above the columns experience tension stresses and lower surface portions of the slab above the columns experience compression stresses. Beams constructed as described may be used as reinforcing heads in the slab above the columns, but in such use the wide tension reinforcing flange should be uppermost and the narrow compression reinforcing flange should be lowermost.

It will be understood that various departures may be made from the construction shown as illustrating the invention without departing from the spirit and scope of the claim.

What I claim as new and desire to secure by Letters Patent is:—

The combination with a concrete slab, of a reinforcing beam therefor comprising a relatively small compression reinforcing head extending longitudinally of the beam and located in said slab adjacent the surface portion thereof under compression, a tension reinforcing flange extending longitudinally of the beam, and a shear reinforcing web interposed between and connecting said flange and head, said head having rigid anchoring projections integral therewith and distributed at intervals along the length thereof for locking the head to said surface portion under compression, whereby the compression strength of the concrete is utilized to prevent longitudinal movement of the beam relative to the concrete.

In testimony whereof I have signed my name to this specification.

EDWARD SMULSEN.
